PENDANT

Ade Bethune, Newport, R.I., assignor to Terra-Sancta Creations, Inc., Philadelphia, Pa.

Original design application Nov. 18, 1970, Ser. No. 26,064, now Patent No. 225,560, dated Dec. 19, 1972. Divided and this application July 31, 1972, Ser. No. 276,388

Term of patent 14 years

Int. Cl. D11—01

U.S. Cl. D45—16 A

FIG. 1

FIG. 2

FIG. 1 is a front elevational view of a pendant showing my new design; and

FIG. 2 is a rear elevational view.

This is a division of my design application Ser. No. D. 26,064, filed Nov. 18, 1970, now Pat. No. D. 225,560, patented on Dec. 19, 1972.

I claim:

The ornamental design for a pendant, as shown and described.
